COMBUSTION APPARATUS

Joseph E. McAdams, Springfield, Ohio, assignor to
 The Steel Products Engineering Company,
 Springfield, Ohio, a corporation of Ohio

Application June 30, 1939, Serial No. 282,167

9 Claims. (CL. 198—53)

This invention relates to heating apparatus and more particularly to fuel feeding and stoking apparatus for furnaces and the like.

A principal object of the invention is the provision of a power driven fuel feeding and stoking apparatus which is of relatively simple and inexpensive construction and which provides for feeding the fuel from a hopper or the like positioned in spaced relation with respect to the fuel feed opening of the furnace to provide for free opening of the fire doors and to permit access to the fire bed for the purpose of cleaning the fire retort and attending to the fire.

A further object is the provision of such apparatus in which the feeding of the fuel from the hopper is automatically controlled to supply fuel to the furnace as required and to avoid objectionable packing and crushing of the fuel, thereby overcoming undue strain and binding of the feeding apparatus.

A still further object is to provide a combined fuel feeding and stoking apparatus in which a rotary conveyor provides for feeding fuel from a hopper into position to be received by a ram and delivered thereby to a retort with the rotary conveyor feeding only so much fuel to the ram as will be received therein without packing or crushing of the fuel.

Other objects and advantages will be apparent from the following description, the appended claims and the attached drawing, in which:

Fig. 1 is a part section and part plan view taken on the line 1—1 of Fig. 2 and showing a portion of a boiler furnace provided with a fuel feeding and stoking apparatus constructed in accordance with the present invention; and

Fig. 2 is a vertical sectional view of the boiler furnace and fuel feeding and stoking apparatus taken substantially centrally of the feeding and stoking apparatus with certain parts shown in elevation.

Referring to the drawing which illustrates a preferred embodiment of the invention there is shown a furnace 10 which may be of any desired or conventional construction and comprises a front furnace wall 11, a fire door 12, a retort 13 of suitable construction and an opening 14 for supplying fuel to the retort. The fire door 12 provides for access to the top of the fire bed for the purpose of attending to the fire, cleaning out the retort, etc.

A hopper or the like for receiving a quantity of solid fuel such as coal, coke, or the like and supplying the same to the retort of the furnace is indicated at 20, and as shown is positioned in

spaced relation with the front wall of the door 12 at a distance sufficient to permit free opening of the door 12 and ready access into the interior of the furnace for the purposes hereinabove described. The hopper 20 comprises a substantially vertical front wall 21 and a plurality of inwardly and downwardly sloping walls 22, 23 and 24 providing for feeding the fuel material received within the hopper towards an opening in the bottom thereof. The front wall 21 and a portion of the side walls 22 and 24 are cut away adjacent the bottom of the hopper as indicated at 25 and 26 respectively to provide a lateral discharge opening in the lower portion of the hopper.

15 The rotary conveyor 30 is mounted on a vertical axis positioned laterally of the hopper 20 between the hopper and furnace 10 and is adapted to enter the hopper through the lateral opening provided in the lower portion thereof to receive a portion of the fuel contained in the hopper and feed it to a position adjacent the fuel inlet opening 14. As shown the rotary conveyor 30 comprises a central hub 31 and a plurality of laterally extending arcuately spaced arms 32 reinforced adjacent the outer ends by a reinforcing ring 33. As shown in Fig. 1 the arms are displaced from a radial position and rotation takes place in such direction as illustrated by the arrow that the arms move with a sweeping motion 20 which tends to cause the fuel particles to move radially outwardly. A substantially cylindrical housing comprising a top wall 35, a side wall 36 and a bottom wall 37 encloses the rotary conveyor 30 and the lateral opening in the lower portion of the hopper 20. As shown in Fig. 2 the bottom wall 37 of the conveyor housing extends entirely across the bottom of the hopper 20 and provides a closure for the open bottom thereof. The rotary conveyor 30 is journaled 25 in the conveyor housing by means of a shouldered downwardly projecting portion 40 on the hub 31 which takes its bearing in a flanged opening provided in the bottom wall 37 and a vertically extending shaft 41 which is carried by the hub 31 and takes its bearing in a downwardly projecting boss 42 provided on the top member 35 of the conveyor housing. The spindle 41 extends downwardly beyond the lower end of the shouldered portion 40 of the hub and carries a sprocket 43 which is keyed to the hub 31 by the elongated pins 44 and provides for driving the conveyor to effect the rotation thereof.

30 A quantity of the fuel within the hopper is received between the arms 32 of the rotary conveyor and is carried by the arms to a position

adjacent the front of the fuel inlet opening 14 of the furnace where it is discharged through an opening 47 provided in the bottom wall 37 of the conveyor housing. As above described the conveyor arms 32 are so disposed that as the conveyor rotates to feed the fuel towards the furnace the fuel tends to move outwardly towards the periphery of the conveyor housing and will thus be readily discharged from the conveyor by dropping through the discharge opening 47. The side wall 38 of the conveyor housing slopes outwardly and downwardly as shown to facilitate the discharge of the fuel through the opening 47, and the ends of arms 32 approach closely and are correspondingly tapered to avoid escape of fuel around the ends thereof during the feeding movement. To avoid unnecessary grinding or crushing of the fuel as the feeding rotor turns a spacing is provided between the tops of the arms 32 and the top plate 35 of the enclosing housing, and if desired a similar spacing may be provided between the bottom of the arms 32 and the bottom plate 37.

The bottom wall 37 of the conveyor housing is provided with a downwardly extending flange 48 surrounding the discharge opening 47, and the top wall 49 of a ram casing 50 is integrally attached to the lower end of the flange 48. The flange 48 thus provides a spacing between the bottom wall 37 of the conveyor housing and the top wall 49 of the ram casing 50 within which the driving sprocket 43 for the conveyor is positioned. The ram casing 50 extends outwardly beyond the hopper 20 at the end remote from the furnace 10 and is provided at this end with a top plate 51 having an upwardly extending portion 52 which is reinforced by webs 53 and provides a bracket for supporting the power drive means for the feeding and stoking mechanism. The casing 50 is arranged in alignment 40 with the fuel inlet opening of the retort 13 and is provided adjacent the furnace with forwardly extended side walls 55 and bottom wall 56 which are received within the fuel inlet opening 14 and are supported on a flanged ledge 57 provided on the lower front wall 58 of the furnace. A pedestal 59 supports the casing 50 at its end remote from the furnace.

The ram casing 50 thus provides a chamber which is positioned below the discharge opening 47 of the conveyor 38 in alignment with the inlet opening of the retort 13 and is adapted to receive the fuel which is discharged through the opening 47. As shown in Fig. 2 the upper surface of the bottom wall 56 of the ram casing lies in the same plane as the upper surface of the bottom 15 of the retort to provide for the free feeding of the fuel from the interior of the ram casing into the retort.

A ram 60 is slidably mounted within the ram casing 50 and provides for intermittently feeding fuel which is received within the ram casing from the conveyor 38 into the retort 13. The ram 60 comprises a hollow casting provided with a downwardly and forwardly sloping front face 61, a lower bearing slide block 62 and a pair of inwardly extending bosses 63 and 64. A connecting rod pin 65 is mounted within the bosses 63 and 64 and provides for operatively connecting the ram 60 with a connecting rod 66 which extends longitudinally of the casing 50 and provides for effecting intermittent reciprocation of the ram.

A common power means is provided for effecting the rotation of the feed conveyor 38 and

reciprocation of the stoking ram 60. As shown a gear casing 70 is mounted on the upstanding bracket 52 and supports an electric motor 71 which is operatively connected with the gearing within the gear casing by means of a V-belt 72 and a pair of sheaves 73 and 74 mounted on the motor shaft and the gear casing respectively. Suitable reduction gearing controlled by clutch lever 75 is provided within the casing 70 and provides a drive for a vertically extending drive shaft 76 which projects outwardly from the bottom of the gear casing. A crank 77 is keyed to the lower end of the drive shaft 76 and a driving sprocket 78 is mounted on the shaft 76 above the crank 77 and is secured to the crank for rotation therewith by a plurality of elongated pins 79.

Roller chain 82 connects the sprocket 78 provided on the drive shaft 76 with the sprocket 43 provided on the hub 31 of the rotary feed conveyor and provides for effecting rotation of the conveyor whenever the driving motor 71 is put into operation. The sprocket chain 82 extends within the spacing provided between the bottom 37 of the conveyor housing and the top 49 of the ram casing and is protected from the fuel within the hopper and conveyor by the bottom member 37 which closes the bottom of the hopper and the conveyor. A sheet metal housing 83 covers the portion of the sprocket chain 82 which is not enclosed by the bottom 37 of the conveyor housing and top 49 of the ram casing and provides a further protection for the sprocket chain.

The crank arm 77 which is mounted on the lower end of the drive shaft 76 is operatively connected with the connecting rod 66 to effect the reciprocation of the ram 60 by means of a sliding lost-motion connection which provides a dwell in the movement of the ram after each forward and return stroke. This connection comprises a sleeve 85 which is pivotally connected to the crank 77 and is slidably received on the connecting rod 66 between a fixed collar 86 and an adjustable sleeve 87. Outward movement of the sleeve 87 towards the end of the connecting rod 66 is limited by a stop nut 88 which is threaded on the end of the connecting rod and provides for adjusting the spacing between the sleeve 87 and the fixed collar 86. From the foregoing description it will be evident that as the crank 77 rotates the sleeve 85 will slide on the connecting rod between the sleeve 87 and collar 86 and the ram 60 will remain stationary until the sleeve 85 has moved into engagement with collar 86, after which the ram will be moved in a forward feeding direction until the crank reaches the end of its forward stroke. The ram will then remain in this forward position until the sleeve 85 has moved back into contact with the sleeve 87, following which the ram will move rearwardly until the crank has reached the end of the return stroke. The ram is thus intermittently reciprocated in a forward feeding stroke and a rearward return stroke and the relative period of dwell at the end of each of these strokes can be readily controlled by adjusting the stop screw 88 to vary the spacing between the fixed collar 86 and the adjustable collar 87 making it possible to vary the time of dwell of the ram or to eliminate the dwell entirely if desired.

In the operation of the device the drive motor 71 is energized and causes the rotation of the rotary conveyor 38 to continuously feed fuel from the interior of the hopper 20 to the discharge

opening 47 provided adjacent the front of the furnace. The fuel thus fed drops through the discharge opening into the chamber provided by the ram casing and is intermittently advanced into the retort 13 through the opening 14 by the reciprocatory movement of the ram 60. During the forward stroke of the ram the top portion thereof serves as a wall preventing the passage of any of the fuel into the portion of the ram casing in the rear of the ram. The dwell of the ram after each stroke thereof provides for the feeding of a sufficient quantity of new fuel to replace that which has been fed into the fire box by the ram.

If the rotary conveyor feeds more material than is being fed into the furnace by the ram the excess fuel does not discharge through the opening 47 but is merely carried around with the arms 32 as they rotate towards the hopper 20, thus avoiding objectionable packing or crushing of the fuel within the ram casing and any strain or binding in the parts of the feed rotor. During the subsequent movement of the arms 32 within the feed hopper only such additional material will be picked up as will be carried between the arms. The feeding of the fuel is thus automatically controlled by the construction and operation of the rotary conveyor itself and without the necessity for any special operation on the part of an operator or any special mechanism connecting with the power drive so that proper feeding action is secured at all times and throughout the range of adjustment of the stroke of the ram.

The present invention is of particular advantage in the case of relatively small stokers applied to fire box type steel boilers. There are many installations of such boilers in which the stoker cannot be so positioned as to make it possible to locate firing doors beneath the water leg of the boiler. It is common practice in such cases, therefore, to use the firing doors of the boiler for the purpose of attending the fire and cleaning the fire box. In accordance with the present invention the hopper may be spaced sufficiently far from the boiler to permit free opening of the boiler firing doors and ready access to the fire bed of the boiler fire box, and a relatively simple, inexpensive and highly effective means is provided for conveying the fuel from the hopper to the furnace and feeding it into the fire box.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A fuel feeding apparatus of the character described for feeding solid fuel to a retort comprising a hopper adapted to receive a quantity of solid fuel, rotary feeding means adapted to enter said hopper through an opening in the lower part thereof for receiving fuel from said hopper and discharging said fuel at a position spaced laterally from said hopper, said rotary feeding means comprising a plurality of arms mounted for rotation about a substantially vertical axis and having open vertically extending passages therebetween through which fuel received from said hopper is adapted to move downwardly under the action of gravity in a generally axial direction, a housing overlying said rotary feeding means, the upper surface of said arms being

spaced below the walls of said housing and of said hopper to provide a clearance space for preventing crushing of the fuel therebetween, a bottom wall for said housing having an aperture 5 therein spaced from said hopper and in line with the path traversed by said arms to discharge fuel downwardly from between said arms, and additional means positioned below said discharge opening for receiving the fuel discharged through said opening and for feeding the same into a retort, said rotary feeding means providing for discharging through said aperture only such quantity of fuel as removed by said additional feeding means while retaining the remainder therein without substantially packing or crushing thereof.

2. A fuel feeding apparatus of the character described for supplying solid fuel to a retort having a door providing for access thereto comprising a hopper spaced away from said door and adapted to receive a quantity of solid fuel, rotary feed means adapted to enter said hopper through an opening in the lower part thereof for receiving fuel from said hopper and discharging said fuel at a position spaced from said hopper, said feed means being rotatable about a substantially vertical axis positioned laterally of said hopper and toward said retort so that fuel flows into said rotary feed means in a generally axial direction 25 and intermediate the axis and the outer periphery thereof, a generally cylindrical housing communicating with the lowermost portion of said hopper on the side toward said retort in which said rotary feed means rotates, said housing having an upper wall positioned adjacent but below the level of said door to avoid obstructing access thereto and having a lower wall which is provided with an opening therein adjacent said retort, said rotary feed means comprising a plurality of arms having spaces therebetween and rotatable over said lower wall and said opening to provide for downward movement of the fuel in a generally axial direction under the action of gravity through the spaces between said arms 30 when said spaces are brought into discharge position above said opening, a chamber positioned below said rotary feed means for receiving fuel discharged therefrom, and means movable within said chamber for advancing fuel received therein to a retort or the like, said rotary feed means providing for discharging only such quantity of fuel as will be freely received within said chamber while avoiding substantial packing or crushing of the fuel therein.

3. A fuel feeding apparatus of the character described comprising an upwardly extending hopper, a conveyor housing communicating with said hopper at the lowermost portion thereof and having its major portion extending laterally beyond the projected area of said hopper and having a substantially flat bottom wall provided with a discharge opening located in a position spaced from the hopper, rotary conveyor means mounted for rotation about a substantially vertical axis within said conveyor housing and comprising a plurality of outwardly extending arms with spaces therebetween providing for receiving fuel under the action of gravity by movement in a generally axial direction from said hopper and feeding it downwardly through said bottom discharge opening, a chamber positioned below said discharge opening of the conveyor housing for receiving fuel discharged therethrough, means for rotating said conveyor means to effect continuous feeding of fuel towards said discharge

opening, and means in said chamber for feeding fuel received therein to a retort or the like, and means for effecting intermittent operation of said retort feeding means, said rotary conveyor means providing for discharging only such quantity of fuel as will freely fall through said discharge opening into said chamber therebelow in accordance with the rate of feed of said intermittently operated retort feeding means, and said hopper in cooperation with said conveyor means providing for supplying only such additional quantity of fuel to the conveyor means as has been discharged from the conveyor means through said discharge opening.

4. A fuel feeding apparatus of the character described which comprises a fuel hopper provided with a lower discharge outlet, a rotary feeding member mounted on an axis positioned laterally of said hopper, said feeding member comprising a plurality of laterally extending non-radial arcuately spaced arms each having a substantial depth in a plane substantially perpendicular to the direction of rotation thereof and adapted to rotate within said hopper outlet to receive fuel from the hopper, a housing for enclosing said feeding member, said housing having an opening providing for the discharge of fuel fed by said arms at a position spaced from said hopper, means for rotating said feeding member to effect the feeding of said fuel from said hopper to said discharge opening, a chamber positioned below said discharge opening for receiving the fuel discharged therethrough, and means including a reciprocating ram in said chamber for feeding fuel received therein forwardly, said arms of the rotary feeding member providing for discharging only such quantity of fuel as will freely fall through said discharge opening into said chamber therebelow in accordance with the rate of feed of said ram and for withdrawing fuel not discharged away from the discharge opening.

5. A fuel feeding apparatus of the character described which comprises a fuel hopper provided with a lower discharge outlet, a rotary feeding member mounted on an axis positioned laterally of said hopper, said feeding member comprising a plurality of laterally non-radially extending arcuately spaced arms each having a substantial depth in a plane substantially perpendicular to the direction of rotation thereof and adapted to rotate within said hopper outlet to receive fuel from the hopper and to carry it in an arcuate path and with a sweeping motion causing the fuel to move radially outwardly thereof, a housing for enclosing said feeding member, said housing having an opening providing for the discharge of fuel fed by said arms at a position spaced from said hopper, means for rotating said feeding member to effect the feeding of said fuel from said hopper to said discharge opening, a chamber positioned below said discharge opening for receiving the fuel discharged therethrough, and means including a reciprocating ram in said chamber for feeding fuel received therein forwardly, said arms of the rotary feeding member providing for discharging only such quantity of fuel as will freely fall through said discharge opening into said chamber therebelow in accordance with the rate of feed of said ram and for withdrawing fuel not discharged away from the discharge opening.

6. A fuel feeding apparatus of the character described which comprises a fuel hopper provided with a lower discharge outlet, a rotary feed-

ing member mounted on a substantially vertical axis positioned laterally of said hopper, said feeding member comprising a plurality of laterally extending non-radial arcuately spaced arms each having substantial depth in a substantially vertical plane and adapted to rotate within said hopper outlet to receive fuel from the hopper, a housing for enclosing said feeding member, said housing having a bottom opening providing for the discharge of fuel fed by said arms at a position spaced from said hopper, means for rotating said feeding member to effect the feeding of said fuel from said hopper to said discharge opening, a chamber positioned below said discharge opening for receiving fuel discharged therethrough, a reciprocating ram positioned in said chamber for feeding fuel received therein forwardly, and means for effecting intermittent reciprocation of said ram, said arms of the rotary feeding member providing for discharging only such quantity of fuel as will freely fall through said discharge opening into said chamber therebelow in accordance with the rate of feed of said ram and for withdrawing fuel not discharged away from the discharge opening.

7. A fuel feeding apparatus of the character described which comprises a fuel hopper provided with side walls and a lower discharge outlet, a rotary feeding member mounted on a substantially vertical axis spaced laterally of said side walls of the hopper, said feeding member comprising a plurality of laterally extending arcuately spaced arms each having substantial depth in a vertical plane and adapted to rotate within said hopper outlet at the bottom of said hopper to receive fuel from said hopper by movement thereof under the action of gravity under a generally axial direction into the spaces between said arms as required to fill the same, a housing for enclosing said feeding member extending laterally of said hopper at approximately the level of the outlet therein, said housing having a bottom opening providing for the gravity discharge of fuel fed by said arms at a position spaced from said hopper, a chamber positioned below said discharge opening for receiving fuel discharged therethrough, a ram slidable within said chamber for feeding fuel received therein forwardly, common drive means for effecting reciprocating movement of said ram and for rotating said feeding member to effect the continuous feeding of said fuel from said hopper to said discharge opening, and means for adjusting the rate of feed of said ram independently of said rotary feeding member to effect controlled supply of fuel, said arms of the rotary feed member providing for discharging only such quantity of fuel as will freely fall through said discharge opening into said chamber therebelow in accordance with the rate of feed of said ram and for withdrawing fuel not discharged away from the discharge opening.

8. A fuel feeding apparatus as defined in claim 2 in which the means movable within the chamber for advancing fuel received therein to the retort or the like comprises a reciprocable ram slidably mounted in said chamber.

9. A fuel feeding apparatus as defined in claim 2 including means for continuously operating the rotary feed means, and additional means for intermittently operating the means movable within the chamber for advancing fuel received therein to the retort or the like.

JOSEPH E. McADAMS.
